J. F. WEILEP.
CONCRETE RAILROAD TIE.
APPLICATION FILED MAR. 12, 1908.

905,035

Patented Nov. 24, 1908

UNITED STATES PATENT OFFICE.

JULIUS F. WEILEP, OF BRADDOCK, PENNSYLVANIA.

CONCRETE RAILROAD-TIE.

No. 905,035.

Specification of Letters Patent.

Patented Nov. 24, 1908.

Application filed March 12, 1908. Serial No. 420,681.

To all whom it may concern:

Be it known that I, JULIUS F. WELLEP, a citizen of the United States of America, residing at Braddock, in the county of Allegheny and State of Pennsylvania, have invented certain new and useful Improvements in Concrete Railroad-Ties, of which the following is a specification, reference being had therein to the accompanying drawing.

10 This invention relates to railroad concrete ties and the objects of my invention are, first, to provide a novel concrete tie of a durable construction; second, to provide a reinforced concrete tie that will withstand the stresses 15 and strains set up by rolling stock passing over the same; and third, to provide novel fasteners for retaining rails upon my tie.

I attain the above objects by a tie that will be presently described and then specifically 20 claimed.

Referring to the drawing forming part of this specification, Figure 1 is an elevation of Fig. 2 is a plan of the same. Fig. 3 is a longitudinal sectional view of a portion of the tie, and Fig. 4 is a cross sectional view of the same, taken on the lines $x-x$ of Fig. 3. Fig. 5 is a horizontal sectional view of a portion of the tie, showing the embedded abutment plate for the bolt heads in 30 plan.

To put my invention into practice, I provide a tie made of concrete and reinforced by metallic rods to add rigidity and strength to the same. My tie is oblong and of dimensions similar to the present type of wooden ties, but I desire it to be understood that the tie can be made of any length according to the use of the same.

A suitable mold or machine is employed 40 for making my tie, either in a factory provided therefor, or in the vicinity of where the tie is to be used. My concrete tie is formed with recesses or cavities 1 and with seats 2 for rails 3. The recesses 1 serve to 45 lighten the tie and cheapen the construction thereof without in any manner weakening it. The seats 2 of the tie are provided with diagonally disposed recesses 4 and with narrow slots 4' which communicate with the recesses through one wall of the latter. The slots 4' at their lower ends communicate with the cavities 5 within the body of the tie, said

cavities being also in communication with the recesses 4 at the lower ends of the latter, the lower part or portion of the recesses 4 and 55 the cavities 5 together with the slots 4' forming substantially T-shaped recesses in which the fastener bolts are received and held as will be later described. In the seats 2 are embedded slotted plates 2^a, these plates being 60 arranged in the fastener recesses 4 at the lower ends of the slots 5.

The rail fasteners which I use in connection with my tie comprise base plates 6 having depending flanges 7 for resting upon the 65 rail seat and providing a space between said plates and the seat, the object of which will presently appear. These base plates 6 are retained in engagement with the rails 3 and the seats 2 by bolts 8 and nuts 9. The bolts 70 are placed in the recesses 4 with the heads 8' thereof downward, and are then moved so that the shank of the bolt passes into the slots 4' of the tie and the notch 2' of the plate 2^a, the head 8' of the bolt being received in the cavity 5. The plates 6 are then placed on the threaded ends of the bolts and secured by the nuts 9. The plates 2^a prevent the heads of the bolts from cutting 75 into the concrete.

The space between the rail seats and the plate 6 permits of the nuts 9 being screwed upon the bolts 8 to force the plate 6 downwardly upon the base flanges of a rail, thus obtaining a more positive grip upon the rail 85 than if the space were not provided.

My tie is reinforced by metallic members preferably in the form of twisted steel bars 10. These twisted steel bars are arranged within the sides of the tie and in the bottom 90 thereof, as illustrated in Fig. 4, thus providing a channel shaped reinforcement adapted to fully protect the tie.

Having now described my invention what I claim as new, is;—

A reinforced concrete tie having rail seats provided with diagonally-disposed vertical recesses, said seats also provided with narrow vertical slots communicating with the recesses and having cavities communicating 100 with the lower ends of the vertical slots and recesses, notched abutment plates embedded in said tie directly over said cavities with the notches therein registering with said ver-

tical slots, bolts seated in said vertical slots and the notches in said plates with their heads received in said cavities and engaging the plates, clamp plates received on said 5 bolts to engage rails mounted on said seats, and nuts on the bolts to secure said clamps in position.

In testimony whereof I affix my signature in the presence of two witnesses.

JULIUS F. WEILEP.
